J. J. WEEKS.

Sausage Stuffer.

No. 2,329.

Reissued Aug. 7, 1866.

Fig. 1.

Fig. 2.

UNITED STATES PATENT OFFICE.

PURCHES MILES, OF NEW YORK, N. Y., ASSIGNEE OF JOHN J. WEEKS.

IMPROVED SAUSAGE-STUFFER.

Specification forming part of Letters Patent No. 11,706, dated September 19, 1854; Reissue No. 2,329, dated August 7, 1866.

To all whom it may concern:

Be it known that JOHN J. WEEKS, of Buc-
ram, in the county of Queens and State of New
York, did invent a new and useful Improvement
in Rotating Sausage-Stuffers; and the fol-
lowing is hereby declared to be a full, clear,
and exact description of the same, reference
being had to the accompanying drawings, forming
part of this specification, in which—

Figure 1 is a vertical longitudinal section of
the machine as it appears when in operation.
Fig. 2 is a vertical transverse section of the
same through the line *x x* in Figs. 1 and 3.
Fig. 3 is a horizontal section of the machine
through the line *y y* in Figs. 1 and 2.

Similar letters of reference in each of the
several figures indicate corresponding parts.

The nature of the said invention consists in
a revolving cylinder and conveyer or conveyers
eccentric to the cylinder or case, in combi-
nation with a hopper for containing meat,
and with a tube through which the sausage-
meat is delivered and stuffed into a gut or other
case. A movable tube is also provided, through
which the sausage passes to determine its size
and prevent the intestine bursting by the
pressure.

To enable others skilled in the art to make
and use the invention, its construction and op-
eration are described.

A in the accompanying drawings represents
a stationary hollow cylinder provided with a
stand or base, B, to rest upon. It is also pro-
vided with a tangential discharge-spout, C,
and with feed-passage and hopper D, as shown
in Fig. 1.

E is a cylinder inside of the cylinder A, and
having journals that revolve freely in bearings
formed on the said cylinder A eccentric to the
axis of the same, as shown in the drawings.

The cylinder E is formed with radial grooves
F F', which intersect each other and pass en-
tirely through the cylindrical portion and are
as wide as the interior of the case A.

G G' are sliding plates or conveyers placed
in the grooves F F'. These plates are made to
act as scrapers and conveyers for taking the
meat from the hopper and carrying it round to
the discharge-spout C as the cylinder is re-
volved. The conveyer G is made with a slot,
a, in its center and G' has an open slot, *b*, in

each of its sides, and is divided at its center,
as represented. The slot *a* allows of the con-
veyer G passing through the cylinder E and
moving radially back and forth in the groove
in the same as the cylinder revolves. The
open slots *b b* allow the conveyer G to move
radially back and forth as the cylinder re-
volves. It is by setting the cylinder E eccen-
tric to the cylinder or case A that the desired
movement is given to the conveyers as the
cylinder is revolved.

By examining the drawings it will be seen
that one portion of the periphery of the cylin-
der E is always in contact, or nearly so, with
the part *c* of the inner circumference of the
cylinder or case A, as said part *c* is above the
discharge-passage C, and either of the con-
veyers is moved inward as far as it is capable
of moving when in contact at one end with the
part *c*. There is no chance of the meat be-
ing carried round past said point *c*, and con-
sequently it must be discharged continuously
by the tube at *c*, as in consequence of the meat
being taken continually from the hopper D
by one of the conveyers and carried around
and forced out at this tube C.

I is a tube placed on the spout C and secured
by a lug, *e*, or other means. This tube serves
for receiving the case or gut, and is provided
with a shoulder, *f*, of sufficient depth to allow
of gut of great length being placed on the tube.
The gut is placed over the tube in the manner
shown in Fig. 1 in red color. On the under
side of the tube I a small air-tube, J, is placed.
It is open at both ends, and when the gut is
drawn over the tube its forward end is closed
by the same, and consequently when the meat
is forced into the gut or case the air in the
same will be caused to pass through said tube
and escape at its back end, as shown by red
arrows, and thus all danger of bursting the
gut or confining the air in with the meat is
avoided.

K is a swinging arm carrying the shaping
and protecting tube L. It is attached to the
ears *g g* of the cylinder A by a fulcrum-pin, *h*.
The tube L is attached to the arm K by the
eye or guide-piece *i i*, and slides loosely back
and forth, so that the arm may be thrown up
to a vertical position out of the way when it is
desired to place the gut on the tube I.

The tube L serves for giving the proper even shape to the sausage as fast as it is stuffed, and also takes off all extra pressure when more meat than the diameter of the gut can contain is forced into the same.

A series of tubes, as shown in the drawings, may be placed inside of the tube l, so that different-sized sausages may be made when desired.

The operation of the machine is very simple. The gut is pulled off the tube the desired length and fastened at its end. The meat is placed in the hopper and the shaft turned continuously. Blades or conveyers take the meat from the hopper and discharge it continuously through the passage C into the case, as illustrated plainly in the drawings. The length of one sausage being stuffed the gut is pulled off another length and filled in like manner, and so on until the whole gut is filled. The proper

even shape being given to the same along its entire length by the tube L, and the air being excluded through the tube J, as before stated.

What is claimed as the invention of the said JOHN J. WEEKS, and to be secured by Letters Patent, is—

1. The revolving cylinder and conveyer or conveyers eccentric to the case or cylinder, in combination with a hopper for containing the meat, and with a tube through which the sausage-meat is delivered and stuffed into a gut or intestine, substantially as set forth.

2. The shaping and protecting tube K, in combination with the delivery-tube I, substantially as and for the purposes specified.

Dated this 2d day of July, A. D. 1866.

PURCHES MILES.
